UNITED STATES PATENT OFFICE.

AXEL JOHNSON, OF OAKLAND, CALIFORNIA, ASSIGNOR TO AMERICAN CAN COMPANY,
A CORPORATION OF NEW JERSEY.

CAN-END-FLANGING MECHANISM.

1,040,953.

Specification of Letters Patent.

Patented Oct. 8, 1912.

Application filed December 5, 1910. Serial No. 595,611.

To all whom it may concern:

Be it known that I, AXEL JOHNSON, a citizen of the United States, residing at Oakland, in the county of Alameda and State of California, have invented certain new and useful Improvements in Can-End-Flanging Mechanism, of which the following is a specification.

The invention relates to an improved apparatus for flanging the ends of cylindrical can bodies to prepare the same to receive and have seamed thereto the can ends or heads, the object of the invention being to dispense with the use of the flanging rolls and associated spinning mechanism commonly employed for flanging over the ends of the can bodies, and to provide an automatic end flanging machine of a simple, effective and durable construction for use in can making factories for flanging can bodies prior to receiving an end or head and in canning factories for flanging the end of filled cans to which heads are to be applied and by means of which the ends of the can bodies may be flanged by a single operation of a reciprocating flanging plunger die movable toward and from the open end of a retained or clamped can body, the said reciprocating flanger die acting against the inner wall surface of the can end to be flanged and gradually turning over or flanging outwardly the entire circumferential end of the body as a single operation.

The flanging mechanism comprises a cooperative combination of a rotary carrier furnished with a plurality of flanging dies, a longitudinally reciprocating flanging die which registers successively with the flanging dies of the rotary carrier, a vertically reciprocating flanging plunger die, and means for imparting an intermittent movement to the rotary carrier and successively throwing into action the reciprocating flanging die and the vertically reciprocating flanging plunger die.

In the accompanying drawings to which reference is hereto made—Figure 1 is a side elevation of the improved can end flanger, illustrating the various parts in normal position, and disclosing the drive mechanism for actuating the rotary carrier and the connections for operating the reciprocating flanging die and the flanging plunger die. Fig. 2 is a plan view of the rotary carrier and the flanging dies carried thereby, said view dis-

closing the segmental guard plate for holding the can bodies in position within the segmental flanging dies of the carrier as carried beneath the flanging plunger die, and the position of the reciprocating flanging die when in registry with one of the dies of the rotary carrier. Fig. 3 is a part sectional side elevation of the parts disclosed by Fig. 2 of the drawings. Fig. 4 is a detail view of the adjusting means for regulating the throw of the flanging plunger die. Fig. 5 is an enlarged detail part sectional view illustrating the segmental flanging dies in registry, a can body held therein, and the position of the plunger die after having flanged the end of the can body. Fig. 6 is a detail view of the cam grooved disks for controlling the action of the reciprocating segmental flanging die and the reciprocating flanging plunger die.

In the drawings, the numeral 1 represents the frame of the machine, the same being of any suitable form capable of giving support to the other parts. Through this frame extends the vertical shaft 2, carrying at its upper end an intermittently rotating carrier 3 provided with a plurality of upwardly extended segmental external can flanging dies 4, each of which is adapted to partly embrace a can body 5.

The shaft 2 supporting the rotary carrier 3 is extended through a sleeve 6 situated within the frame of the machine and adjacent its lower end has secured thereon a radially slotted wheel 7, which is intermittently driven by an engaging roll 8 carried by and depending from a gear 9. This gear is mounted on an upright shaft 10, driven from the main drive shaft 11 through the medium of the intermeshing bevel gears 12 and 12', the former of which is on the main drive shaft 11 and the latter on the upright shaft 10. Under this construction an intermittent or Geneva stop movement is thus imparted to the shaft 2 and carrier 3 from the main drive shaft 11.

The gear 9 meshes with a gear 13 carried by the lower end portion of the sleeve 6 for transmitting continuous movement to the said sleeve and the parts carried thereby.

Each of the segmental flanging dies 4 of the rotary carrier 3 is provided or furnished with an upwardly extended segmental wall extension 14, which in conjunction with a similar wall extension 14' of the longitudi-

nally reciprocating segmental flanging die 15 serves when the flanging dies are in registry, as a guide extension of the flanging dies for the vertically reciprocating flanging 5 plunger die 16, and into which guide extension the end of the can body to be flanged projects.

The reciprocating segmental flanging die 15 is secured to a slide 17 working through a 10 guide 17' on the frame of the machine, and this slide is connected to an operating fulcrumed lever 18 by a link 18'. In order that the flanging die 15 may move into perfect registry with the segmental dies 4, the same 15 is provided with the projecting lugs or tongues 15' which move into engagement with the countersunk seats 4' in the face of each of the flanging dies 4.

Above the rotary carrier 3 and in alignment with the segmental flanging dies 4 and 15 when in registry is held a vertically reciprocating flanging plunger die 16, the stem 16' of which works through guides 17' sustained by the overhang portion of a 25 bracket or standard 19 upwardly projecting from the machine frame, and the said plunger die is raised and lowered by means of the lever 18' fulcrumed to the said standard 19. This lever at one end is pivoted to the 30 plunger stem 16' and at its opposite end secured by the toggle link connections 20 and 21 to the adjustable screw-threaded post 22, the said toggle connection being in turn connected to the fulcrumed operating lever 35 23 by the link connection 23'. The post 22 extends through the guide shelf 22' and is raised and lowered by the adjusting nuts 24 and 25, which work against the upper and lower faces of the shelf 22'.

40 The sleeve 6 is a continuously rotating one and on the same is secured the spaced disks 26 and 26', and to properly throw the reciprocating flanging die 15 and the flanging plunger die 16 and thus cause each of the 45 said dies to be properly reciprocated in unison with the intermittently rotary carrier 3, which carries the flanging dies 4, at each stop or period of rest of the carrier 3, there is provided for the fulcrumed levers 18 and 50 23 the operating links 27 and 27', which at their free ends carry the rolls 28 and 28'. The roll 28 works within an irregular cam groove 27^a cut in the under face of the disk 26, while the roll 28' works within an irregular 55 cam groove 27^b cut in the upper face of the disk 26'.

The can bodies 5 to be flanged are delivered in any suitable manner onto the rotatable carrier 3 and within the segmental 60 flanging dies 4, so that the end to be flanged projects a slight distance above the flanging surface or edge *a* and *a'* of the flanging dies 4 and 15 when in registry. As the horizontally intermittently rotary carrier 65 projects the can bodies toward the flanging

mechanism, the said bodies are held within the segmental flanging dies 4 by the segmental guard plate 29, which partly encircles the rotary carrier 3. When the held can body is in alignment with the flanging 70 plunger die 16, the carrier 3 comes to a state of rest, and during such pause in the rotation of the rotary carrier 3 the rotary motion of the disk 26 through the described connection throws inwardly the reciprocating slide 17 carrying the flanging die 15 to place the same in registry with the flanging die 4, when the movement of the disk 26' is transmitted through the described connections to lower the reciprocating flanging 75 plunger die 16 into the guide extension of the registered flanging dies. As the said die 16 is forced its full downward distance, the inclined or beveled face 16² enters within the open end of the held can body and gradually compresses outwardly and turns over the projecting end of the can body, the circumferential shouldered portion *b* of the die 16 finally acting to compress the can flange *b*' onto the flanging surfaces *a* and *a'* of the registered flanging dies. After the end of the clamped can has been flanged the rotary movement of the disk 26', through the medium of the roll 28' working in the cam groove 27^b of the said disk, imparts 90 motion to the link 27' to draw inwardly the lower end of the fulcrumed lever 28, throwing outwardly its upper end thereof and through the described connections actuating the fulcrumed lever 18' to throw upwardly 100 its inner end for lifting the vertically movable stem 16' to carry the plunger die 16 from within the guide extension of the registering segmental flanging dies. At the same time the movement of the disk 26 will 105 impart a reverse action to the connections for actuating the slide 17, causing the flanging die 15 to move away from the flanging die 4, by which time the roll 8 of the gear 9 will actuate the radially slotted wheel 7 to 110 impart a step rotation to the carrier 3 for taking the flanged can body from within the sphere of the flanging plunger die and advancing an unflanged can body beneath the same.

To permit of the reciprocating flanging die 15 to move into registry with the flanging die 4 without interference with the segmental guard plate 29, the said flanging die 15 is slotted at 5^a transversely in order to permit of the die straddling the segmental guard plate 29 as moved inwardly.

By providing for an adjustment to the post 22 the throw of the plunger flanging die 16 may be varied to accommodate the stroke 125 thereof to can bodies to be flanged.

The reciprocating internal plunger die 16 acts on the entire surface of the end to be flanged and by so doing turns over the metal at a single operation, thus overcoming the 130

splitting of the end metal which follows from the employment of flanging rollers which act successively against small sections of the circumferential wall of the projecting 5 end to be flanged.

The working of the various parts of the apparatus is entirely automatic, and the working of the associated parts so timed as to come into action at the proper moment.

10 Having thus described the invention what is claimed as new and desired to protect by Letters Patent is—

1. In a can body end flanging machine, the combination with a rotary carrier having a plurality of external segmental flanging dies, of a reciprocating external segmental flanging die coöperating with the flanging dies of the carrier, a vertically reciprocating internal flanging plunger die, 20 and means for imparting movement to the said flanging dies.

2. In a can body end flanging machine, the combination with a rotary carrier provided with a plurality of external segmental 25 flanging dies, of a segmental wall coacting with said dies for holding can bodies therein, a reciprocating external segmental flanging die for registering successively with the flanging dies of the rotary carrier, and a reciprocating internal flanging die for flanging the end of can bodies held between the 30 said external flanging dies when in registry.

3. In a can body end flanging machine, the combination with a rotary carrier provided with a plurality of external flanging dies, of a reciprocating external segmental flanging die coacting with the dies of the rotary carrier, each of said mentioned dies being provided with an external segmental 40 wall extension, and a reciprocating internal flanging die coöperating with the external segmental flanging dies for the described purpose.

4. In a can body end flanging machine, the combination with a rotary carrier provided with external segmental flanging dies, of means for imparting an intermittent movement thereto, a reciprocating external segmental flanging die registering successively 50 with the rotary traveling segmental dies, a vertically reciprocating internal flanging plunger die coöperating with the external segmental flanging dies, and means for imparting motion to the mentioned reciprocating dies.

5. In a can body end flanging machine, the combination with an intermittent rotary

carrier, provided with a plurality of external segmental flanging dies, of a reciprocating external segmental flanging die registering successively with the said flanging dies, a slide carrying the reciprocating die, means for reciprocating the slide toward and from the rotary carrier, and a vertically reciprocating internal flanging plunger die 65 coöperating with the segmental flanging dies when in registry for the described purpose.

6. The combination with an intermittent rotary can supporting carrier provided with a plurality of external segmental flanging 70 dies, of a reciprocating external segmental flanging die coacting successively with said dies, and an internal flanging plunger die coöperating with the segmental dies for flanging the end of a can body held between 75 said dies.

7. In a can body end flanging machine, the combination with a rotary can supporting carrier, of a plurality of external segmental flanging dies upwardly extended 80 from said carrier and each provided with a segmental wall extension, coacting successively with said dies for clamping a can body therein, and a reciprocating can body flanging die conforming in shape to the 85 mouth of the can to be flanged, and means for moving the said die into and out of the guide formed by the wall extensions of the segmental dies when in registry for flanging the end of the clamped can extended 90 therein.

8. In a can body end flanging machine, the combination with a rotary can supporting carrier, of a plurality of external segmental flanging dies upwardly extended 95 from said carrier and each provided with a segmental wall extension, a reciprocating slide, an external flanging die provided with a segmental wall extension carried thereby, means for actuating said 100 slide to place its die in registry successively with the dies of the carrier, a reciprocating internal can body flanging die, and mechanism for moving the same into and out of the guide extension formed 105 by the segmental wall extensions of the external segmental dies while in registry.

In testimony whereof I have signed my name to this specification in the presence of two subscribing witnesses.

AXEL JOHNSON.
